(57) **CLAIM**

I claim the ornamental design for a angle grinder power tool, substantially as shown.

DESCRIPTION

FIG. 1 is a perspective view of the angle grinder power tool. FIG. 2 is an opposite perspective view of the angle grinder power tool.

FIG. 3 is a side view of the angle grinder power tool.

FIG. 4 is top view of the angle grinder power tool.

FIG. 5 is a bottom view of the angle grinder power tool.

FIG. 6 is a front view of the angle grinder power tool; and, FIG. 7 is a rear view of the angle grinder power tool.
